UNITED STATES PATENT OFFICE

MENNO YAGGY, OF LOS ANGELES, CALIFORNIA, ASSIGNOR OF ONE-THIRD TO H. H. AMSTUTZ, OF DENAIR, CALIFORNIA, AND ONE-THIRD TO EMIL ERHART, OF LOS ANGELES, CALIFORNIA

WINDOW-POSITIONING ORGANIZATION

Application filed March 16, 1927. Serial No. 175,704.

As may be inferred from the above title, this invention relates to means favorable to the retention of a window sash in a desired relationship to a window frame; and, in preferred embodiments of my invention, I may equip each window sash, assuming the same to be pivoted upon hinges, with means, preferably independent of said hinges for yieldably holding the same in a predetermined position; and I may use, in conjunction with the mentioned holding means, retracting means comprising a pull chain, and jamb-attached tightening means,—the latter being especially suitable for use upon long or high windows, in order to complete a tightening movement thereof, at will; and it is an important merit of the organization referred to that, the major parts thereof being suitable for independent manufacture, sale and use, they are all cooperative in effect, and all suitable for use on windows which are provided not only with outwardly disposed sashes but with inwardly positioned screens.

Other objects of my invention, including a provision of means for varying the position to which a sash may be biased by means tending to draw one inner edge (adjacent to a pivoted edge) toward an opposite jamb; and including a provision of means for varying the tension of a spring by which a sash may be drawn or biased and held in a predetermined open position, and including also the provision of means rendering the described jamb-attached tightening means applicable either to a sliding sash or to a pivoted sash and adapting the same to use upon either a right-hand jamb or a left-hand jamb, and including also a novel end-restraining member suitable for use upon a retracting chain, as hereinafter described, may be best appreciated from the following description of an illustrative embodiment of my invention, taken in connection with the appended claims and the accompanying drawings, in which

Fig. 1 is a vertical sectional view of a window organization embodying features of my invention,—taken substantially as indicated by the line 1—1 of Fig. 5, with the parts broken away.

Fig. 2 is a partial horizontal sectional view,

taken substantially as indicated by the line 2—2 of Fig. 1.

Fig. 3 is a sectional detail view, taken substantially as indicated by the line 3—3 of Fig. 2.

Fig. 4 is a perspective view, separately showing a preferred type of slideable hook, and a preferred type of keeper, suitable for cooperative use in a manner best indicated in Fig. 2.

Fig. 5 is a horizontal sectional view, taken substantially as indicated by the line 5—5 of Fig. 1.

Fig. 6 is a horizontal sectional detail view, taken substantially as indicated by the broken line 6—6 of Fig. 1.

Fig. 7 is an elevational detail view, taken substantially as indicated by the arrow 7 of Fig. 6.

Fig. 8 is a perspective view, separately showing an adjusting device, as viewed from the general direction indicated by the arrow 8 of Fig. 5.

Fig. 9 is a perspective detail view, showing an end restraining member, suitable for use upon a retracting chain, this view being taken from the general direction implied by the arrows 9 of Figs. 6 and 7.

Referring to the details of that specific embodiment of my invention, chosen for purposes of illustration, 11 and 11' being respectively jamb members of a window frame, I show a sash 12 comprising stiles 13, 13' as pivoted upon a vertical axis by means of ordinary hinges 14.

The sash 12 being outwardly disposed; I show a window screen 15 as occupying a fixed inner position; and, in order to provide for an automatic opening movement of said sash, or for a biasing of the same toward a predetermined open position, at the same time providing for the retraction of the same by means such as a chain 16 (shown as extending through a notch 17 in the frame 18 of the mentioned screen) I now prefer to employ separate resilient means such as a tension spring 19,—an outer end thereof being shown as secured to the stile 13 of the sash 12 by means of a bracket 20, and the inner end of said spring being secured, directly or in-

directly, to a horizontal element 21 of the mentioned window frame.

The bracket 20 is shown as inwardly terminating in a bent end 22, provided with an eye 23, and as retained by means of screws 24. In order to provide for a variation or predetermination of the angle at which the sash 12 is yieldably held by the spring 19, or its equivalent, the bracket 20 may, if desired, be 10 provided with longitudinally-extending slots 25 rather than round holes, to receive the screws 24; but, unless it is considered important that the sash 12 be yieldably held at an angle of about 90° or more, relatively to a 15 wall in which the frame comprising jambs 11, 11' and horizontal elements 21, 21' is secured, it may be considered unnecessary to so shape or adjust the bracket 20 as to extend the same, as shown at 26, beyond the vertical surface 20 27, of the stile 13; and, accordingly, unnecessary to bore or cut away the jamb 11', in the manner suggested at 28, to permit the sash 12 to close. The inner end of the spring 19 being preferably so bent as to form an eye 25 29, instead of inserting a nail or screw directly therethrough into the horizontal frame element 21, I may, if desired, employ, at the inner end of the spring 19, adjustable means such as a threaded bolt 30. This bolt is 30 shown as provided with an opening 31, engaged by the mentioned eye in spring 19, extending through upstanding ears 32, 32', in a bracket 33, secured by screws 34,—an adjusting nut 35 being adapted to engage a threaded 35 section 36 of said bolt.

To provide for closing, at will, the sash 12, or its equivalent, by means such as the mentioned chain 16, and for holding the same tightly closed, notwithstanding the opening 40 tendency of the spring 19, or its equivalent, I may advantageously secure the outer end of said chain to the stile 13', or its equivalent, by means having the general character best shown in Fig. 6. That is to say, disposing a 45 compression spring 37 within a retaining member such as a cup 38, a central aperture 39 through the convex wall 40 of said cup being of such diameter as to permit the chain 16 freely to move therethrough. I may, utilizing 50 the interior surface of said wall as a stop for said spring, and extending the chain 16 through said spring, provide the inner end of the chain with a stop member such as a "button" 41.

55 In order to permit the use of a comparatively shallow cup 38 (shown as secured by screws 42) with a fairly long spring 37. I may recess the stile 13', as suggested at 43; and, in order to hold the chain 16 in a retracted position, after the same is drawn inward, with the spring 37 under some compression, I may provide, on the jamb 11 and inwardly of the frame 18 of screen 15, slotted retaining means of any suitable char- 60 acter.

For the purpose last referred to, I show a bent and slotted bracket 44, secured by a screw or screws 45, as provided with a key-hole slot 46, and as adapted to cover the notch 17, in the frame 18,—only the larger end of 70 said keyhole slot being of such diameter as to permit movement of the chain 16 therethrough. The inner end of the chain 16 may be secured in any suitable way; but I prefer to provide thereon an end-restraining member in the form of a plate 48,—shown as provided with an opening 49 for the attachment of said chain and with a diagonally-extending notch 50 upwardly terminating in a horizontal edge 51. This edge, when engaging an enlarged portion of a link of the chain 16 may supplement or take the place of the action of the keyhole slot 46 in so engaging a link of the chain 16 as to hold the sash 12 in a closed position. 75

Although the organization, as herein described, may be regarded as entirely complete for use upon a window of ordinary size and shape, under usual conditions, in the case of uncommonly long or high windows which are required to stand open during considerable periods of such weather as might occasion a warping of sash elements, I consider it advantageous to use, in conjunction with parts of the general character described, one or more jamb attached tightening devices, manipulable from within the mentioned screen, and comprising slidable bolts outwardly terminating in hooked or bent ends, releasably engageable by keepers secured to 100 the stiles or other element of a window sash.

For the purpose last referred to, I may, for example, provide a slidable, 2-part or other bolt 52, with a knob or handle 53, at its inner end, and with a bent or hooked end 54, at its opposite end,—adapted to engage any suitable keeper 55, secured to a sash. I show the 2-part bolt 52 as comprising a tubular section 56 and a rod like section 57, adjustably interfitting therein and integral with the bent end 54,—a "plate" 58 being preferably provided, on said rod like section for engagement by a set-screw 59; and the 2-part bolt 52, or its equivalent, may be guided, and so secured as to permit both longitudinal and 110 rotational movement, by means such as spaced bearing brackets, an inner bearing bracket 60 being shown as secured to a stop element 61 of the jamb 11 and an outer bearing bracket 62, shown as secured to said jamb by screws 63, being adapted to serve also as a stop for compression spring 64, confined between and centered by said bracket and the knob or handle 53.

Although I may use, with the bolt 52 or its equivalent, a keeper of any preferred type, I show the keeper 55 as comprising an attachment plate 65 and a cam plate 66,—extending at right angle thereto; and an engagement of the hooked or bent end 54 with inclined 125

- surfaces such as are shown at 67, 67' may be adapted, when the knob or handle 53 is suitably rotated, assuming the sash, to have been nearly closed, to occasion an inward or tightening movement of said sash, and also to place the spring 64, or its equivalent, under an appreciable compression,—constantly drawing and resiliently holding the sash against a vertical surface 68 of the stop 61.
- 5 10 By providing a plurality of symmetrically disposed inclined surfaces 67, 67' upon each of the keepers 55, I may adapt each keeper to be used either upon a right-hand stile or a left-hand stile; and by inwardly terminating 15 the mentioned cam surfaces in notches 69, 69', I am able to rely upon the action of the spring 64 to retain the hooked or bent end 54 of the bolt 52 in engagement with a keeper, of the general character described, until man- 20 ual readjustment shall be effected (by means of the knob or handle 54,—as for the purpose of opening the window comprising the sash 12, without disturbing the screen which comprises frame 18).
- 25 It will be seen that, depending upon the position of attachment of the plate or bracket 20 and the power or adjustment of the spring 19 the sash 12 may be biased, with any desired force, toward a preferred open position; 30 that the interposition of the spring 37 at the outer end of the chain 16 provides, when the chain is pulled inward and held in the general manner described, for resiliently drawing toward a closed position that portion of the 35 sash 12 to which the cup 37 may be attached; and that any desired plurality of the described jamb-attached tightening devices may be used upon such sash as are deemed to require the same, by reason of length or conditions of use, to assure a perfectly tight or 40 weather-excluding fit, or to obviate or correct warped condition thereof.
- The springs 64 being such as incidentally to prevent unintended release from the keepers 55, bent ends 54 of the described hooked bolt 52, or its equivalent, may, if desired, be biased toward an out-of-the-way position, as by suitably winding the spring 64 and inserting its respective ends 70 and 70' in depressions or holes 71, 71', respectively formed in the knob or handle 53 and the mentioned guide or outer bearing bracket 62; and accordingly the described jamb-attached tightening members and cooperating keepers may, 55 when suitably shaped and positioned be used even upon sliding sash.
- 45 My invention permits the use of simple, common, rugged hinges 14, involving no removal or disturbance of hinges upon which 60 my devices are tardily installed; and it is an important merit of the described means for biasing a sash toward an open position that the spring 19, or its equivalent, may occupy a somewhat protected and partially concealed 65 position beneath a stop strip 72, shown as
- secured by screws 73,—this stop strip being presumably of exactly the same breadth as stop strips 61, on the jambs 11, 11'; and it is also an important merit of the described organization, as the same may be applied to 70 windows not initially equipped therewith, that the cutting away of a horizontal window frame element 21, to provide space for the spring 19 and the bracket 33, or its equivalent, need not be effected with great care, for 75 the reason that the stop strip 72, afterwards secured in the described manner, may serve sufficiently to conceal any splintering of the surface 74, or its equivalent.
- That part of a sash to which the chain 80 16 is directly connected being adequately tightened thereby, it will be understood that the described jamb-attached tightening means need be used, if at all, only upon parts remote therefrom; and that my use of the 85 described set-screw between the parts of my hooked bolt enables me to adapt the same to window organizations in which the screens are disposed at different distances from window sash.
- 90 Although I have herein described a single complete embodiment of my invention, it should be understood not only that various features thereof might be independently employed, but also that numerous modifications 95 of said invention might easily be devised by workers in the art to which this case relates, without involving the slightest departure from the spirit and scope of said invention, as the same is set forth above and in the following claims.
- 100 I claim as my invention:
1. In a window organization having an outwardly disposed window sash hingedly mounted upon a window frame: means for biasing said window sash toward an open position, said means including a spring arranged to exert a pull on the inner side of 105 said sash near the hinged edge thereof.
  2. In a window organization having an outwardly disposed window sash hingedly mounted upon a window frame: means for biasing said window sash toward an open position, said means including a spring arranged to exert a pull on the hinged edge 110 of said sash interiorly of the hinge axis.
- 115 In testimony whereof, I have hereunto set my hand at Los Angeles California, this 11th day of March, 1927.
